UNITED STATES PATENT OFFICE.

PAUL LEVÈQUE, OF BRUSSELS, BELGIUM, ASSIGNOR TO SOCIETE EN NON COLLECTIF
M. THOMAS ET P. LEVÈQUE, OF BRUSSELS, BELGIUM.

AIR-INLET-CONTROLLING DEVICE FOR FURNACES.

Application filed August 26, 1924. Serial No. 734,279.

To all whom it may concern:

Be it known that I, PAUL LEVÈQUE, a subject of the King of the Belgians, residing at Brussels, in the Kingdom of Belgium, have invented certain new and useful Improvements in Air-Inlet-Controlling Devices for Furnaces, of which the following is a specification.

My invention relates to improvements in controlling devices such as are used in combination with the air inlet flap or damper of a steam generator or industrial kiln or oven of the kind in which a coupling connection is provided between the said damper and the furnace door so as to prevent the opening of the said door when the damper is in its open position.

One object of my invention is to secure such a controlling device in which the position of the air inlet damper will be positively independent of the operation of the lever cooperating with the furnace door to maintain the same in its closed position so as to avoid any possibility of the damper being placed in an intermediary position between the position of complete closure or complete opening when the door is left in a corresponding intermediary position.

A further object of my invention is to obtain the required movements of the damper without any separate operation upon the said damper either to bring the same in its open position or in its closed position the said movements being the consequence of the operation of the lever maintaining the furnace door in its closed position.

And a still further object of my invention is to secure improved means whereby the movement of the door lever is only used for starting the corresponding movement of the air-inlet damper, the said damper as soon as its closing movement has been started being brought in its complete closure position under the action of the air under pressure which normally feeds the furnace of the generator or kiln.

With these objects in view my invention essentially consists in the special arrange-

ments and combinations of parts as will be 50 hereinafter fully described and pointed out in the appended claims.

Referring to the annexed drawings which show as an example one embodiment 55 of my invention:

Fig. 1 is a front view of a furnace door and of the corresponding air-inlet conduit.

Fig. 2 is a side elevation of the coupling connection between the door lever and the air damper, showing the said connection in 60 its end positions.

Figs. 3, 4, 5 and 6 are diagrammatic views showing the relative positions between the door operating lever and the connection with the air damper at the various stages 65 of the operation.

In the example shown, 1 is a furnace door adapted to rotate on the hinge 2; the furnace cooperates in the usual and well known manner with the air feeding conduit 3 in 70 which is arranged the air damper 4 (Fig. 2) mounted on the oscillating shaft 5. The said damper is suitably balanced so as to obtain that in a given position, it will oppose a minimum resistance to the current 75 of air under pressure which is circulated in the conduit 3 in the direction of the arrow 6 to be injected in the furnace.

The door 1 is provided as usual with a hand lever 7 which is pivoted at 8 and engages in a hook 9 to maintain the door in its closed position.

According to my invention the said lever 7 is provided with an extension 10 which when the door is in its closed position, is 85 engaged in a notch 11 of a coupling connection or connecting bar 12 which is pivoted at 13 at the end of an arm 14 which is keyed on the shaft 5 of the damper 4 outside the air feeding conduit 3. 90

The connecting bar 12 is further provided with a longitudinal slot 16 in which a guide 17 is engaged the said guide being fixed to the wall of the steam generator or of the furnace.

The device operates as follows:

The furnace door being in its closed position, the lever 7 is engaged behind the hook

9 and rests with its extension 10 within the notch 11 of the connecting bar 12 (Fig. 3). The air damper 4 is then maintained in its open position as shown at 4' in Fig. 2 and 5 the air which is forced in the air conduit 3 as usual is admitted in the furnace.

If it is necessary to open the door 1, the lever 7 is lifted from the hook 9 and rotated on the pivot 8 in the direction of the arrow 18 (Fig. 1). Before the door can be turned into its open position, the extension 10 of lever 7 lifts the connecting bar 12 which sliding on the fixed guide 17, carries with it the arm 14 which causes the shaft 5 and 10 consequently the damper 4 to pivot. As the lever 7 is lifted to be disengaged from the hook 9, the extension 10 of the said lever gradually disengages also from the notch 11 15 of the connecting bar 12 as shown in Figs. 20 4 and 5.

The extension 10 becomes finally completely disengaged from the notch 11 (Fig. 5—see position in dotted lines) when lever 7 25 is in its raised position, out of contact with the hook 9. At this moment the damper 4 is not yet in its closed position but is sufficiently raised to be acted upon by the current of air under pressure circulating in the conduit 3 in the direction of the arrow 6. 30 Under the action of this pressure, the balanced damper 4 is brought in its completely closed position shown at 4 in dotted lines in Fig. 2. This movement of the damper completes the lifting of the connecting bar 12 35 which is further displaced with the slot 16 along the fixed guide 17. This supplemental movement of the connecting bar 12, under the dependence of the damper 4 is necessary to bring the connecting bar 12 in a 40 suitable position to allow the reengagement of the extension 10 of lever 7 with the notch 11 when the reversed operation is effected that is to say at the moment of closing the door. At this moment when the lever 7 is 45 oscillated downwardly to be engaged with the hook 9, the extension 10 of lever 7 acts in the notch 11 (Fig. 5) to bring the connecting bar 12 again into its initial position. Should this supplemental movement 50 of the connecting bar not take place a little displacement of the connecting bar 12 in the downward direction could be sufficient to bring the notch 11 for instance in the position shown Fig. 6 in which the extension 55 10 of lever 7 would strike against the lateral face 19 of the connecting bar. Owing to the supplemental lifting of the connecting bar 12, on the contrary, the said bar will be maintained in the position shown 60 in Fig. 5 in which the arc of circle described by the extension 10 of lever 7 is such that the lower edge 20 of this extension will always strike against the lower edge 21 of the notch 11 thus enabling lever 7 to engage

again the said notch and to displace the 65 connecting bar downwardly whereby the damper 4 will be returned in its open position.

It will be observed that the above described arrangement secures a complete dependence between the position of the damper 4 and the position of the door 1. When the door is in its closed position, the damper 4 is in its open position and when the lever 7 is lifted to release the door, damper 4 is 70 first closed partially under the action of the positive control resulting from the use of the connecting bar 12, the closure being subsequently completed under the action of the air under pressure. Any air admission in 75 the furnace is thus prevented in an efficient and certain manner without any other operation than the handling of the oscillating lever 7 controlling the opening and shutting of the furnace door.

What I claim is:

1. In combination with a furnace door and with a damper controlling the air feeding inlet in the said furnace, an oscillating lever operable to permit the closing and opening of the furnace door and a coupling connection between the said lever and the damper whereby the operation of the oscillating lever to permit opening of the door starts the closing movement of the damper. 90

2. In combination with a furnace a door for said furnace, an air feeding conduit co-operating with the said furnace, a damper in the said conduit, an oscillating lever co-operating with the furnace door, whereby the same is maintained in its closed position, a coupling connection between the said lever to initially move the damper in the operation of the lever, the connection between the damper and lever being thereafter interrupted to permit air closing of the damper. 100

3. In combination with a furnace, a door for said furnace, a pivoting lever mounted on the said door, and operating to normally hold the door against opening, an air feeding conduit cooperating with the furnace, whereby the said furnace, may be fed with air under pressure, a damper in the said conduit, a connecting bar, the said bar being provided with a notch in which the door lever is engaged, means for guiding the said connecting bar and a pivoted connection between the said bar and the damper. 110

4. In combination with a furnace door and with a damper controlling the air feeding inlet to a furnace, of means for normally holding the door in closed position, and a connection between said means and the damper to operate the damper a predetermined distance toward closing position in 120 that movement of the means tending to release the door.

5. In combination with a furnace door

and with a damper controlling the air feeding inlet to a furnace, of means for normally holding the door in closed position, and a connection between said means and the damper to operate the damper a predetermined distance toward closing position in that movement of the means tending to re-

lease the door, the damper following such predetermined movement being freed to the influence of the air in said inlet for completing the closing of the damper. 10

In testimony whereof I have affixed my signature.

PAUL LEVÈQUE.
